T. J. LOFTUS.
TURBINE MOTOR AND PRESSURE DEVICE.
APPLICATION FILED FEB. 9, 1910.

978,044.

Patented Dec. 6, 1910.

UNITED STATES PATENT OFFICE.

THOMAS J. LOFTUS, OF CASTELLA, CALIFORNIA, ASSIGNOR OF ONE-HALF TO CHARLES T. LOFTUS, OF CASTELLA, CALIFORNIA, AND ONE-HALF TO HARMON BELL, OF OAKLAND, CALIFORNIA.

TURBINE-MOTOR AND PRESSURE DEVICE.

978,044.

Specification of Letters Patent.

Patented Dec. 6, 1910.

Application filed February 9, 1910. Serial No. 542,866.

To all whom it may concern:

Be it known that I, THOMAS J. LOFTUS, a citizen of the United States, residing at Castella, in the county of Shasta and State of California, have invented new and useful Improvements in Turbine-Motor and Pressure Devices, of which the following is a specification.

This device relates to that class of motors wherein a plurality of disks provided with wings or blades, or other form of impact surfaces are caused to rotate by fluid under pressure, whether the same be constant or intermittent, and relates more particularly to the means whereby the flow of motive fluid is controlled and directed to the power-imparting mechanism.

The invention consists of the parts and the construction and combination of parts as hereinafter more fully described and claimed, having reference to the accompanying drawings, in which—

Figure 1 is a vertical longitudinal section. Fig. 2 is a transverse section on line *a—a* of Fig. 1. Fig. 3 is a transverse section on line *b—b* of Fig. 1. Fig. 4 is a transverse section on line *c—c* of Fig. 1. Fig. 5 is a detail view illustrating the igniter. Fig. 6 is a detail view illustrating the starting device.

A is a base upon which is supported the operating mechanism, the same consisting of means whereby the motive fluid is controlled, and means whereby the same is utilized to cause a rotation of a series of disks. The latter means consist of a cylinder 1 having a head or cap 2, in which is journaled the end of a shaft 3; the opposite end of said shaft is journaled in the head 4, the same being provided with a longitudinal extension 5, the purpose of which is to provide bearing for a series of rotatable disks 7. Said disks are provided on their periphery with a series of radial wings or blades 8 which may be concavo-convex, or other suitable configuration, and so situated that the impact of motive fluid against the same, will tend to rotate the adjacent disks in opposed directions. The faces of said disks are provided with suitable circular racks 9, into which mesh pinions 10 adapted to rotate freely upon studs 11 revoluble in the extension 5.

Suitable means are provided whereby the bearing of the disks on the extension 5 is

lubricated, the same consisting of passages 12, communicating with the passage 13 in 55 the shaft 3.

Secured to the shaft 3 is a disk 14 which receives the final impact of the motive fluid, and is connected to revolve in unison with the disks 7. Secured upon the rear face of 60 said disk is a suitable raceway 15; a like raceway 16 being provided in the head 2. Adapted to travel between the raceways 15—16 are a series of balls 17, the same serving as an antifriction and thrust bearing. 65 A suitable exhaust opening 19 is provided in the head 2 whereby the spent fluid is allowed to escape.

The head 4 is provided with a waist portion 20, and a flange 21, to which is secured 70 by means of bolts the plate 22, upon which the controlling valves are mounted. Situated within the waist 20 are the valve chambers 23 in which reciprocate the valves 24, the same controlling the communicating passages 25 between the disk housing 1 and the explosion chamber 26, the latter having partitions 27 whereby chambers are provided for each set of inlet valves, and the igniter for same. To permit of a free movement of 80 the valves 24 in either their active or passive stroke, a small port 28 communicating with the valve chamber and the atmosphere through a second port 29 is provided.

The valve 24 is operated to close the passage 25 by means of a spring 30 encircling the stem 31 of valve 24, the same abutting at one end against the stuffing-box of the valve stem, and the other against the collar 32. The said valve is operated in its active 90 stroke by the expansion of gases which are admitted to the explosion chamber through and around the valves 33.

Secured to the plate 22 is a valve housing 34 having supply ports 35 for air under 95 pressure, and a port 36 for the admission of gas, or a combustible volatilizing liquid. A suitable passage 37 is provided in the said valve, one end of which is constantly in communication with chamber 26, while the opposite end is adapted to open and close communication with the passage 36.

A waist portion 39 is provided on the stem of the valve 33 by which communication for air admission is established between chamber 100 26, and the port 35. The movement of valve

33 in one direction is effected by means of a spring surrounding the stem thereof between the stuffing-box, and the tappet-head 40.

6 Journaled on, and near the end of shaft 3, 6 is a revolving sectional tappet disk 41 encircled by the ring 42, and upon studs secured to the same are rollers 43, the same adapted to contact with the tappet head 40, to operate valve 33 to its open position. Secured to disk 41 is a circular rack 44, into which meshes the pinion 45, the same being secured to the master-wheel 46, and rotating with same, and is driven by means of the pinion 47 secured to the shaft 3. By this 15 construction the power disks 7 may revolve at high speed, and the speed of the disk 41 be reduced through the medium of the gear connection to the main shaft.

The wheel 46 is adapted to revolve freely 20 upon a stud carried by the standard 47, the same being supported upon the standard 48, secured to the base A.

Suitable means is provided whereby the initial starting of the motor may be effected, 25 the same consisting of a handle 50, secured to the ring 42 and rotating with same. Upon the interior of said handle is a plunger 51 having lateral projecting thumb-pieces 52, whereby the plunger may be retracted 30 against the action of the projecting spring 52. The outer end of plunger 51 is adapted to enter a perforation in the upturned flange of the disk 41, whereby the disk 41 and the ring 42 will be held in engagement.

35 The means employed to effect ignition is shown in Fig. 5, and consists of two parts, one, 60, permanently secured against movement, and insulated against the metal parts, and the other, 61, insulated in like manner. 40 The part 61 is operated by means of a spring to produce a spark between the contact points, and in the opposite direction by means of the tappet rollers 43. Secured near the upper ends of the spark plugs 60 and 61 45 are flanges or collars 62—63, the same adapted to maintain a complete circuit at all times when not operated, and shifting the direction of current from the collars 62 and 63 down one spark plug, and up the other, when 50 the spark points are in contact; the electric conductor from the battery or dynamo having connection to the upper end of the spark plugs. By this arrangement, the mechanism employed to produce a spark is always in 55 circuit with the next succeeding sparking apparatus whether there are two or more, or in other words the same will be arranged in series.

Having described the construction, the 60 operation is as follows: Motive fluid, or an explosive mixture, is held under pressure exterior of the valve housing, and the valves within the same seated. Under such conditions it is necessary to first charge the 65 explosion chamber by operating the valve 33;

this operation being effected by rotating the ring 42 a portion of a revolution. This is effected by first disengaging the ring 42 from the flange on disk 41 and retracting the plunger 51, when the said ring may be given a partial revolution, bringing the tappet rollers 43 in contact with a tappet 40 on the stem of the valve 33, thus opening the communicating ports between the explosion chamber and the exterior supply, when the 70 said chamber will receive its charge. A further partial rotation will then bring the tappet rollers in contact with the movable part 61 of the igniter, thus closing the circuit through the contact points. A continued 75 movement of said ring will allow the moving section of the igniter to retract and open the circuit, and spark across from one point to the other, and ignite the charge within the explosion chamber, and shift the valve 24, 80 thus opening the explosion chamber to the disk chamber through the passages 25, when the fluid so generated will escape, and impact against the wings on the disks, and cause a rotation of same alternately in opposite directions; the power of each disk being imparted to the final disk secured to the shaft 3, which will rotate same, and operate all parts connected therewith; the plunger 57 being released it engages a notch in the 95 rim 41, thus engaging the ring 42 thereon.

The arrangement of valves and igniter may be modified from that here illustrated, and so arranged that each and every valve may be operated during every revolution of 100 the main shaft, or any number of explosions may be had per revolution, the same being controlled by the number of tappet rollers carried by the ring 42.

Having thus described my invention, what 105 I claim and desire to secure by Letters Patent is—

1. In a turbine motor, the combination of a turbine housing, a series of combustion chambers at one end thereof, means for delivering explosive fluid under pressure to said chambers, said means including air and gas inlets and normally closed valves controlling said inlets, means for operating the valves to permit the fluids to enter the explosion chamber, means for exploding said fluid in the chambers, said housing having passages connecting its interior with the explosion chambers, and horizontally slidable valves normally closing the inlet to said 115 passages and actuated by the gases of the exploded charge to direct the exploded fluid to the interior of the housing and to the turbine disks, a drive shaft adapted to be revolved by said disks, and connections between the shaft and the first named valves 120 for operating the latter.

2. In a turbine motor, the combination of a drive shaft, a plurality of revoluble turbine disks adapted to revolve said shaft, a 125

- housing for said turbine disks, a series of combustion chambers at one end of the housing, said housing having passages connecting its interior with said chambers, means 5 for admitting explosive fluid under pressure to the combustion chambers, said means including air and gas ports and valves controlling said ports each valve controlling a pair of ports and having a longitudinal passage through it, means for operating the valves to admit the explosive fluid to the chambers, means for exploding the fluid in said chambers, and valves normally closing the passages between the chambers and the 10 interior of the housing, said last named valve being operated by the gases of the exploded charge.
3. In a turbine motor, a drive shaft, a plurality of revoluble turbine disks adapted 20 to revolve said shaft, a housing for said turbine disks, a series of combustion chambers on said housing, normally closed valve controlled passages connecting said combustion chambers with the interior of said housing, 25 ports for the admission of fluids under pressure to said combustion chambers, normally closed valves between said ports and said chambers, means on said drive shaft for opening said valves to admit fluids through
- 30 said ports into said chambers, and means by which said valves may be operated independent of said drive shaft.
4. In a turbine motor, a series of combustion chambers, valve-controlled ports for admitting explosive fluids under pressure to 35 each of said chambers, means for normally retaining said valve ports closed, a revoluble ring, contact rollers on said ring, and means by which said ring may be revolved so that said rollers will open said valve-controlled 40 ports to admit fluids to said chambers.
5. In a turbine motor, a series of combustion chambers, ports for admitting explosive fluids under pressure to each of said chambers, normally closed valves between said 45 ports and said chambers, sparking mechanism for exploding fluids in said combustion chambers, a revoluble ring, means on said ring by which said valves and said sparking mechanism may be operated, and means 50 for revolving said ring.

In testimony whereof I have hereunto set my hand in the presence of two subscribing witnesses.

THOMAS J. LOFTUS.
